ARMCHAIR KEY SWITCHES
Major Felten, Galesteo, N. Mex.
(P.O. Box 2233, Santa Fe, N. Mex.)
Filed Jan. 24, 1961, Ser. No. 84,618
4 Claims. (Cl. 200—159)

This invention relates to manually operated electric switches and more particularly to a slide operated switch having characteristics which especially suit it for armchair use for the muting of loudspeakers.

A switch for armchair use must be capable of operation by a force so slight it will not be displaced from the chair arm. It must be capable of operation by one hand of the user. It should be economical in cost, rugged in construction and foolproof in operation.

The improved switch of the present invention fulfills the foregoing requirements in a manner described in the following description read with reference to the accompanying drawing made a part of this specification and in which:

FIGURE 1 is an isometric view partly in section.

FIGURE 2 is a longitudinal central sectional view on section 2—2 of FIGURE 1.

FIGURE 3 is a cross sectional view on section 3—3 of FIGURE 1.

FIGURE 4 is a cross sectional view on section 4—4 of FIGURE 1.

FIGURE 5 shows an alternative embodiment.

Referring to the drawing, FIGURE 1, the switch comprises a body element 11 and an operator element 13. Both the body element and the operator element are preferably formed of insulation material such as, for example, wood, rubber or synthetic plastic. Stationary body element 11 is an elongated hollow member having a gently convex upper configuration inclined downwardly from front to rear in a generally streamlined fashion. The lateral walls also taper from front to rear. The bottom edge of the opposed side walls and end walls of the body may lie on a common plane at the bottom to provide a generally flat surface for resting on an armchair. The lateral exterior surfaces of the switch body are provided with elongated recesses 12. The foregoing described shape is such as to permit the palm of the hand to straddle the switch body with the thumb on one side resting in the flute and the remaining fingers other than the forefinger resting in the flute on the other side of the housing, thereby grasping the switch.

The movable operator element 13, hereinafter termed "key," is the switch actuating handle. This member opens circuits the switch by a first downward and then a forward motion. To this end a recess 14 is provided in which the forefinger rests. The grasping of the stationary body element 11 by one hand with the index finger resting in the key recess 14 of movable operator element 13 enables the user to operate the switch in a completely comfortable and convenient manner with the forearm and hand in reclined position as on the arm of an armchair.

Stationary body element 11 is provided with an elongated channel of rectangular cross section which extends through the body from top to bottom except at the ends. At the rear or tail end a bridge 15 joins the channel walls and at the front end a solid nose portion 17 of the body 13 is provided.

Key 13 has a loose or clearance fit in the body element 11 channel in order that it can be moved within the body element to close or open the switch contacts in a frictionless manner.

Key 13 is provided with a substantially flat bottom surface and an arcuate upper surface similar in configuration to the top surface of body element 11.

2

Referring to FIGURE 2 it is seen to be provided with a horizontal cross-wise elongated slot 19 proximate its rearward end to pivot on and translate forward and aft on pivot pin 21 best seen in FIGURE 4. Pin 21 is supported with a snug fit in cross-wise bore or socket 23 in body element 11.

When key 13 is nested in the body element 13 channel, and pin 21 is in place, the operator element is free to rotate about pin 21 in a limited arc and also free to move back and forth due to the provision of slot 19.

The underside of the forward end of operator element 13 is relieved in step fashion to provide lip 25. Lip 25 cooperates with upper surface 27 of body nose 17 to stop the downward motion and to provide a guide for forward sliding motion key 13 when urged downward and forward by the forefinger of the user.

Referring to FIGURES 1 and 2, it is seen that the inner surface of nose portion 17 of the stationary body is provided with two stepped surfaces 29 and 31. A flat electrical contact element 33 is supported against the underside of the first step 29 which is the one proximate the forward end of the stationary body portion 11 channel. The flat contact may be supported in any convenient manner and in the embodiment shown, see particularly FIGURE 3, it is integral with a depending metallic strap 35 which fits in a recess 37 in the side wall of the relieved nose portion. A horizontal extension 41 of the depending strap is nested in a relieved portion of the base of the nose portion and secures the entire contact member as by screw or screws 39. The horizontal extension or tab 41 provides a terminal for the switch contact element 33.

The other switch contact element 43 is affixed to the bottom surface of key 13 by an elongated extension portion 45. An offset portion 47 is provided preferably integral with contact portion 43 and extension 45 of a length such that when the operator element 11 is depressed the contact element 43 lies in a plane slightly below the second step 31 of nose 17. This clearance permits the operator to be moved forward so that contact element 43 will rest and be retained under insulator ledge 31 to maintain the switch in "off" position.

When key 13 is moved backward to the limit permitted by slot 19, contact element 43 clears ledge 31 and is free to rise and contact stationary contact element 33 thereby "closing" the switch.

It is necessary in a switch for the purpose herein intended that it have an "easy" action. The user's finger depresses the key 13 and resilient means of gentle action must be provided to cause the key to be urged in an upward direction. To this end cantilever blade spring 51 is provided. Spring 51 is anchored in a recess 53 (see FIGURES 2 and 5) in the tail end of stationary body portion 11. It has an inherent upward curve ending in the front end in a downturned anti-friction bent portion 55. The upper surface of bent portion 55 makes electrical contact at all times with the extension portion 45 of contact element 43. A conducting lead 57 is electrically connected to spring 51. A second conducting lead 59 is connected to stationary contact terminal 41 and the two leads pass out of the switch body through a bore or perforation 61 for the purpose provided preferably in nose portion 17.

The bottom of the switch assembly is closed by a sheet or plate of insulating material 63 which is glued in place.

The bottom surface of the switch stationary body 11 is shown to be flat in the embodiment described but bearing in mind that a primary purpose of the switch requires that it be utilized on an armchair arm, it obviously can be contoured when the occasion demands to more closely fit a curved or rounded upper surface of an armchair arm.

It is also contemplated that the switch body and key

may be of molded construction. In this event the construction can be simplified to provide the pivoted and sliding support of the tail end of the key in the tail end of the bottom portion. The tail end of body 11 is closed upon itself by the bottom portion 15, the side walls and forwardly extending top portion 65. The construction provides an elongated socket 67 into which the tail end of the key is seated and in which it has limited but frictionless freedom of motion with respect to pivoting and forward and rearward motion. The key 13 is provided with a reduced tail portion 69 of generally uniform cross section to fit in socket 67. In this embodiment the switch contact 43 is left in a depending direction until after the key is positioned in body portion 11. The contact 43 is then bent forwardly to provide the contact element and also to secure the key within body portion 11. In this embodiment, the slot 19, pivot pin 21, and cross-wise socket 23 of the first embodiment described are not necessary.

It is therefore seen that there has been provided by this invention an electrical switch particularly adapted for easy and convenient operation on an armchair by the inclined arm and hand. Obviously, it may profitably be used as a push button switch in other situations where a push button switch not anchored down may be easily operated by one hand as adjacent a telephone, for example.

Because many possible embodiments may be made of the above invention and as many changes might be made in the embodiments above set forth, it is to be understood that all matter hereinabove set forth as shown in the accompanying drawing is to be interpreted as illustrative and not in a limiting sense.

What is claimed is:

1. An electrical switch comprising an elongated housing of insulation material, and an elongated switch operating bar key of insulation material, said housing having spaced elongated side walls joined at a front end by a nose portion and at the other end by a tail portion, said key having a width which provides a clearance fit in the space between the side walls and having a forward end and a rearward end, said forward end being relieved on its underside, means pivotably and slidably affixing the key rearward end to the housing tail portion, said key having a length such that when it is so affixed to the body

portion the key portion over the relief in the front end is in a superposed position over the body nose portion upper surface, first and second stepped depending ledge portions on the underside of the upper wall of the body nose portion, said second ledge depending a greater distance than the first ledge, a first electrical contact element affixed to the bottom surface of the first ledge, a second electrical contact element having an elongated portion, a depending portion and a forward extending portion, and having the elongated portion affixed to the underside of the key and said forward extending portion being coextensive with the key front end relief, resilient spring means urging said key upward, whereby when the key is in rearward position, the contacts are connected and when the key is depressed and moved forwardly, the second contact rests against the nose portion second ledge thereby maintaining the contacts in unconnected relation.

2. The switch of claim 1 in which the body portion and key element taper down laterally and vertically from nose portion to rear portion, said body portion being provided with a lengthwise elongated flute on each lateral wall, and a recess in the key forward end top surface whereby said switch may be grasped by the reclined hand with the forefinger in the key recess to thereby manually select an off or on electrical condition for said switch.

3. The switch of claim 1 wherein the means for pivotably and slidably affixing the key rearward end to the housing tail portion is a journal pin affixed crosswise in said housing and a journal pin cooperating slot in the key rearward end portion.

4. The switch of claim 1 wherein the means for pivotably and slidably affixing the key rearward end to the housing tail portion is a socket in the housing tail portion provided by the housing rear end floor, lateral walls, and a forward extending wall over the housing rear end floor, and said key rearward portion having a clearance fit in said socket.
